UNITED STATES PATENT OFFICE.

EDWIN P. WANNER, OF NEW YORK, N. Y.

DESIGN FOR A CHAIR.

Application filed September 8, 1928. Serial No. 28,074. Term of patent 7 years.

To all whom it may concern:

Be it known that I, EDWIN P. WANNER, a citizen of the United States, and resident of the borough of Manhattan, city, county, and State of New York, have invented a Chair, of which the following is a specification, reference being had to the accompanying drawing, forming part thereof.

Fig. 1 is a perspective view of a chair showing my new design and Fig. 2 is a top plan view thereof.

I claim:

The ornamental design for a chair, as shown.

EDWIN P. WANNER.
